UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

PROGRAM-SELECTING CIRCUITS.

Application filed December 10, 1923. Serial No. 679,733.

This invention relates to transmission systems for sending programs over wires, and more particularly to arrangements for the selection of programs for such systems.

5 Where wire lines, such as ordinary telephone lines, for example, are used for the transmission of entertainment programs, such as news, lectures, concerts and the like, it is desirable that some arrangement be 10 provided whereby the subscriber may automatically select the particular program which he desires to hear. In accordance with the present invention, it is proposed to accomplish this result by providing a selective switch at the central office which may be directly controlled by an operator to connect the terminals of the subscriber's line to the terminals of any one of a number of trunks each leading to a different program. When 15 the subscriber desires a particular program, he can then call up over his telephone line in the usual manner and inform the operator of the program which he desires, and the operator can then connect that program to 20 the line.

By the use of a directly controlled selective switch for selecting a program, it becomes immaterial whether the program be transmitted at voice frequencies or carrier frequencies, and it also becomes immaterial whether the several programs be transmitted at the same frequency or whether different carrier frequencies are used for different programs. By permitting the directive switch 30 to be controlled by the operator rather than the subscriber, circuit complications due to dialing over the subscriber's line are eliminated.

40 The invention will now be more fully understood from the following description when read in connection with the accompanying drawing, the figure of which illustrates a circuit arrangement whereby a directive switch may be used to select programs.

50 Referring to the drawing, L designates an ordinary telephone transmission line terminating in the usual subscriber's set S at one end and terminating at the central office in the multiple jacks J and J'. Normally the telephone line L is connected over the contacts of a cut-off relay CO to a transformer 20, whereby the line is associated with conductors 11 leading to a directive switch DR

for connecting the line with the desired program. The line relay LR has its windings connected on either side of the condenser 21 intermediate between the two halves of the secondary winding of the transformer 20. The cut-off relay CO is so arranged that 60 when it is operated the line L is disconnected from the transformer 20 and hence from the line relay LR, and is connected directly to the tip and ring terminals of the multiple jacks J and J'. 65

In order that the line may be used for program transmission during such time as it is not being used for ordinary telephone purposes, a program receiver such as the loud speaker LS is provided at the subscriber's 70 station, said receiving device being bridged across the line through the back contact of the switchhook 10 and through the contact of a relay 23. The relay 23 is so arranged that it will be operated to connect the loud speaker to the line upon the momentary actuation of the upper contact of the non-locking key K. On the other hand, the relay 23 is so arranged that it will be released to disconnect the loud speaker upon taking the 80 receiver from the switchhook to make a call or upon the operator inserting a plug into one of the multiple jacks to call the subscriber. It may also be released by the subscriber when he no longer desires to hear a 85 program by momentarily opening the lower contact of the key K.

At the central office the wipers 25 and 26 of the directive switch DR are arranged to connect the conductors 11 to any one of a 90 plurality of trunks A, B, C, D, E, etc., leading to different voice frequency programs. In order to operate the switch DR a stepping magnet SM is provided, said magnet being controlled by means of a dial 24. The 95 stepping magnet SM is associated with a jack J'' into which a plug P'' may be inserted to associate a dial 24 with the stepping magnet. By properly manipulating the dial 24, the switch DR may be advanced directly under the control of the stepping magnet SM. A release magnet RM is also provided for restoring the switch to normal under certain conditions, such release relay being under the joint control of relays 27 105 and 28, as will be described hereinafter. The switch is so arranged that it will be operated step by step under the control of the

dial and will be released and restored to J'' and plug P'' and over contacts 32 and 29 of the dial to ground.

Further details of the apparatus will be clear from the description of the operation which is as follows: When the line L is not in use for telephonic purposes and the subscriber desires to hear a program, such, for example, as the program C, the subscriber 10 will remove his receiver from the switchhook 10, thereby operating the line relay LR to call the attention of the operator at the central office. The operator inserts a plug in the answering jack J in the usual manner, 15 thereby operating the cut-off relay CO and connecting the line L to the jack J. Upon ascertaining the program desired by the subscriber, the operator will withdraw the plug of her cord circuit from the answering jack 20 J, thereby releasing the cut-off relay CO and again connecting the line L to the conductors 11 through the transformer 20. The operator then inserts the plug P'' in the jack J'' and operates the dial 24 in the same 25 manner as is customary in the operation of machine switching dials. For example, the dial may have each of its holes provided with a letter corresponding to each of the programs. The operator, in the case assumed, 30 will insert her finger in the hole marked "C" and rotate the dial until her finger comes against the stop, when the dial is released. As soon as the dial begins to rotate, the off-normal contact 29 of the dial 35 is closed and remains closed until the dial is restored to normal after being released. The closing of the off-normal contact completes a circuit from ground, over the contacts 29 and 32, through the contacts of the 40 plug P'' and jack J' and through the winding of slow release relay 27 to battery. Relay 27 is at once energized and is sufficiently slow in releasing its armature so that its armature will not be released through momentary interruptions of the circuit of the dial 24, due 45 to the dialing operation.

Relay 27 at its front contact completes a circuit over the right-hand back contact of relay 28 for the release magnet RM. Relay 27 at the same time closes a circuit for the 50 slow operating relay 28 so that after a moment the relay 28 opens the circuit of the release magnet RM. The momentary energization of the release magnet RM, however, 55 causes the directive switch DR to be released and restored to normal before any impulses are being transmitted from the dial 24, the operations which have just been described taking place while the dial is being advanced. 60 As is well known, the impulses sent from the dial are transmitted after it is released. Relay 28, upon being energized, closes a circuit from battery, over its left-hand front contact, through the winding of the stepping 65 magnet SM, over the contacts of the jack

J'' and plug P'' and over contacts 32 and 29 of the dial to ground. The circuit is now ready for the transmission of dialing impulses and as soon as the dial is released, the circuit just traced through the stepping magnet SM is intermittently opened by the contact 32 of the dial 24. Each time this circuit is interrupted the stepping magnet SM is deenergized and advances the wipers of the directive switch 70 DR one step. When the dial has been completely restored to normal and all of the impulses have been transmitted, wipers 25 and 26 have been advanced to the contacts connecting the conductors 11 to the desired 75 program, which in the case assumed, was the program C. Upon the dial being restored to normal, the off-normal contact 29 is opened and consequently, the slow acting relay 27 is released. This relay in turn 80 opens the circuit of the relay 28, which closes a circuit of the release magnet RM at one point, but the circuit of said magnet has been previously opened by the contact 85 of the relay 27, so that the release magnet 90 is not energized at this time.

In the meantime, the subscriber hangs up his receiver and momentarily operates the non-locking key K to close its contact 33. This completes a circuit from battery 95 through the right-hand winding of the line relay LR, over the lower back contact of the cut-off relay CO, over the ring conductor of the line L, over the back contact of the switchhook 10, over the normally closed contact 31 of the key K, over the momentarily closed contact 33 of said key, through the winding of the relay 23, over the tip conductor of the line L, over the upper back contact of the cut-off relay CO and through 100 the left-hand winding of the line relay LR to ground. Owing to the high resistance of the relay 23, the line relay LR is not actuated by the circuit above traced, but the relay 23 is operated and at its inner front contact completes a locking circuit independent 105 of the contact 33 of the key K. At its outer front contact relay 23 bridges the loud speaker LS across the line so that the subscriber may now listen to the program transmitted over the conductors 11 and through 110 the transformer 20 to the line.

If a call should come in for the subscriber while the circuit is being used for reception of a program, the operator inserts a plug of her cord circuit in one of the multiple jacks, for example, the jack J', thereby energizing the cut-off relay CO. The cut-off relay shifts the connections of the line L from the conductors 11 to the multiple jacks, to which the cord circuit is connected. This momentarily interrupts the circuit previously traced for the relay 23, which releases and opens its locking circuit before a new circuit is 115 established for said relay to the battery 120

associated with the cord circuit. Accordingly, the relay 23 disconnects the loud speaker LS from the line and the subscriber, by taking his receiver from the switchhook, 5 may carry on the telephone conversation.

At the end of the conversation, the subscriber hangs up his receiver and when the operator withdraws the plug of her cord from the multiple jack, the cut-off relay CO 10 is released, again connecting the line L through the transformer to the conductors 11. If the subscriber now wishes to again hear the program, he momentarily actuates the key K to close the contact 33, thereby 15 establishing a circuit for the relay 23 as previously described. The relay 23 again bridges the loud speaker LS across the line L so that the subscriber may continue to listen to the program.

20 If, while the program is being received, the subscriber should desire to make a call, he merely removes the receiver from the switchhook 10. This opens the locking circuit of the relay 23 and causes said relay to 25 be released and disconnect the loud speaker LS from the line in the manner already described. At its upper contact the switchhook 10 completes a low resistance circuit through the line relay LR, as already described. Upon observing the glowing of the 30 line lamp, the operator inserts a plug in the jack J, thereby operating the cut-off relay CO to disconnect the line L from the conductors 11 and connect it to the multiple 35 jacks. The telephone connection is then completed in the usual manner and the conversation proceeds. At the end of the conversation the subscriber hangs up his receiver and upon the connection being taken 40 down, the subscriber can again listen to the program by actuating the key K to close the contact 33, as already described.

When the subscriber desires to discontinue 45 the program connection he operates the key K to momentarily open the contact 31. This releases and unlocks the relay 23, thereby disconnecting the loud speaker LS from the subscriber's line. The setting of the switch DR is not disturbed by this operation. If 50 the subscriber should thereafter desire to change the program, he does so by calling up the operator, as already described, whereupon the operator will plug the dial 24 into the jack J" and dial a new program. As 55 already described, the initial operation of the dial causes the release magnet RM to restore the switch DR to normal so that in response to the pulses transmitted, it will be advanced to the desired program.

60 It will be obvious that the general principles herein disclosed may be embodied in many other organizations widely different from those illustrated without departing from the spirit of the invention as defined in 65 the appended claims.

What is claimed is:

1. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, selective switching means independent of said first mentioned switching means at the central office for establishing a connection between said line and any desired trunk, and controlling means at the central office whereby the operator may control the operation of said selective switching means. 70 75

2. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, a directive switch 80 independent of said first mentioned switching means at the central office for establishing a connection between said line and any desired trunk, and controlling means at the 85 central office whereby the operator may control the operation of said directive switch to select a program. 90 95

3. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, a directive switch 100 independent of said first mentioned switching means at the central office for establishing a connection between said line and any desired trunk, controlling means at the central office whereby the operator may control the operation of said directive switch to select a program, and means for restoring 105 said switch to normal at the beginning of 110 its operation to select a program. 115

4. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, a step-by-step 120 switch independent of said first mentioned switching means at the central office for switching said subscriber's line to a desired trunk, and means at the central office whereby the operator may control said switch. 125 130

5. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, a step-by-step switch independent of said first mentioned switching means at the central office for switching said subscriber's line to a desired trunk, means at the central office whereby the operator may control said switch, and means to restore said switch to normal at the beginning of its operation to select another trunk. 30
6. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, an impulse-operated selecting switch independent of said first mentioned switching means at the central office, an impulse sender at the central office for transmitting impulses to said switch to operate the same to establish a connection between said subscriber's line and any desired trunk. 35
7. In a wired program system, a subscriber's telephone line terminating in a subscriber's telephone apparatus at the subscriber's station, switching means at the central office whereby a connection may be established between said subscriber's line and another subscriber's line, a plurality of trunks at the central office upon which programs may be impressed, an impulse-operated selecting switch independent of said first mentioned switching means at the central office, an impulse sender at the central office for transmitting impulses to said switch to operate the same to establish a connection between said subscriber's line and any desired trunk, and means to restore said switch to normal at the beginning of its 40 operation to establish a connection to another trunk. 45
- 20
- 25

In testimony whereof, I have signed my name to this specification this 7th day of December, 1923.

JOHN F. TOOMEY.
